UNITED STATES PATENT OFFICE.

JOHN E. MCCUSKER, OF NEWBURYPORT, MASSACHUSETTS.

DESIGN FOR A TICKET OR CHECK HOLDER.

SPECIFICATION forming part of Design No. 32,277, dated February 27, 1900.

Application filed January 29, 1900. Serial No. 3,241. Term of patent 7 years.

To all whom it may concern:

Be it known that I, JOHN E. MCCUSKER, a citizen of the United States, residing at Newburyport, in the county of Essex and State of Massachusetts, have invented and produced a new and original Design for a Ticket or Check Holder; and I do hereby declare the following to be a full, clear, and exact description of the same, reference being had to the accompanying drawings, forming a part thereof.

In the accompanying drawings, Figure 1 is a perspective view of a ticket or check holder embodying my design. Fig. 2 is a similar view looking at the same from the opposite side, and Fig. 3 is a vertical transverse section through the same.

The leading feature of my design consists of a comparatively flat rectangular-shaped hollow body portion provided with inwardly-extending spring fingers or prongs and attaching ears or flanges.

1 in the drawings represents the body por-

tion of the device, which is substantially rectangular in shape, as shown, and hollow, the 25 space between the walls 2 and 3 admitting of the insertion and removal of a ticket or check. The wall 3 is provided with inwardly-extending spring tongues or prongs 4, which bear upon the ticket or check and hold the same 30 in position within the body portion of the device. The device is also provided at its ends with perforated attaching ears or flanges 5, as shown.

Having now described my invention, what 35 I claim as new, and desire to secure by Letters Patent, is—

The design for a ticket or check holder, substantially as herein shown and described.

In testimony whereof I hereunto affix my 40 signature in presence of two witnesses.

JOHN E. MCCUSKER.
